CARBURETOR

Edward G. Atkins, Jackson, Mich., assignor to
E G A Carburetor Co., Jackson, Mich., a corpora-
tion of Michigan

Application October 9, 1933, Serial No. 692,774

12 Claims. (Cl. 261—50)

This invention relates to carburetors and it is more particularly adaptable to carburetors for internal combustion engines used in automobiles and is of the same general type as that disclosed in my Patent No. 1,787,230 issued December 30th, 1930.

An object of the invention is to provide a carburetor which will obtain its supply of fuel, which is usually gasoline, from a tank located either above or below the level of the carburetor and will maintain a substantially uniform level of gasoline in the carburetor irrespective of the relative level of the gasoline in the supply tank.

A further object of the invention is to provide a carburetor which will supply a proper mixture of fuel and air under the full range of running conditions to which it is subjected. Another object of the invention is to provide a carburetor which utilizes the gas evaporated from the gasoline line in the float chamber of the carburetor and provides a constant suction within the float chamber which will prevent air locks in the gasoline supply pipe.

The invention provides various new and useful features of construction and arrangement as hereinafter more fully described and particularly pointed out in the claims, reference being had to the accompanying drawings, in which,

Fig. 1 is a vertical sectional elevation of the carburetor embodying this invention, taken on the line 1—1 of Fig. 4.

Fig. 2 is a fragmentary section of the same taken on the line 2—2 of Fig. 4.

Fig. 3 is a fragmentary cross section of the ejecting nozzle taken on the line 3—3 of Fig. 1.

Fig. 4 is a plan view, with the cover removed, of the carburetor with the throttle neck and suction chamber removed.

Fig. 5 is a vertical section through the float portion of the carburetor taken on the line 5—5 of Fig. 4.

Fig. 6 is a transverse vertical section on the line 6—6 of Fig. 4.

Fig. 7 is a vertical section of the dash pot on the line 7—7 of Fig. 4, and

Fig. 8 is a fragmentary vertical section of the air inlet valve on the line 8—8 of Fig. 4.

Like numbers refer to like parts in all of the figures.

1 represents the throttle neck which is attached to and communicates with the intake manifold of an internal combustion engine and is provided with the conventional throttle valve 2. The suction and mixing chamber 3 is attached to and 50 communicates with the throttle neck 1 and has

an air inlet opening 4 provided with a suction valve 5.

The gasoline container, which will be generally termed the float chamber 6, is located adjacent one side of the mixing chamber 3, the bodies 5 of the two chambers being preferably formed separately and joined by screws 7 by means of which their relative axes may be altered to accommodate different conditions of installation. In other words, it is necessary to have the axis 10 of the float chamber substantially vertical while the carburetor neck may be attached to the manifold of the engine at different angles depending upon the construction of the engine, and the screw connection 7 will permit the float chamber to be mounted with its axis vertical regardless of the position of the throttle neck and mixing chamber.

The suction valve 5 has a stem 8 which is slidably mounted in a guide 9 and is provided with an extension in the nature of a push rod 10 mounted in a guide 11. This division of the valve stem 8 and push rod 10 is for convenience of construction and assembly and the two members can be integral if preferred.

Fuel ejecting passages 12 are located at opposite sides of the valve stem 8, extending through the same element 9 in which the valve stem guide is located and these passages communicate outwardly with the mixing chamber 3 and inwardly with a chamber 13 surrounding the push rod 10. A U-shaped passage 14 communicates with the float chamber above the gasoline level and also with the chamber 13 and the gasoline control valve 15 admits gasoline from the float chamber to the passage 14 as hereafter described.

It will be understood that suction produced by the engine will open the suction valve 5 to admit air through the passage 4 and this movement actuates the valve stem 8 and the push rod 40 10 to move the bell crank lever having an arm 16 and pivoted within the float chamber at 17. The bell crank lever has a transverse body portion 18 from which a short arm 19 extends and also has an arm 20 upon the swinging end of which the contact rollers 21 are mounted.

The bell crank lever operates to open and close the gasoline control valve 15 in synchronism with movement of the suction valve 5 and the gasoline control valve 15 is provided with a spring 22 acting to close it and also, through connections hereinafter described, to close the suction valve 5 and a spring 23 in a dash-pot 24, acting against the rollers 21 on the arm 20 of the bell crank, also tends to close the suction valve 5 and open- 55

ing movement of the suction valve acts against the tension of both of the springs 22 and 23.

A rocking lever 25, supported on an adjustable fulcrum 26, has one end pivotally connected at 5 27 to the gasoline control valve 15 and its opposite end is connected by a link 28 to the short arm 19 of the bell crank lever. By this connection opening movement of the suction valve 5 produces opening movement of the gasoline 10 valve 15.

It is desired to "dampen" or prevent too rapid opening movement of the suction valve 5, this being accomplished by the piston 29 operating in the dash pot 24 against tension of the spring 23.

15 The dash pot 24 has a vent passage 30 communicating with its upper end and extending downward into the float chamber below the gasoline lever which constitutes a restricted outlet and permits a relatively slow upward movement of 20 the piston 29 in the dash pot. This vent passage, having its outlet below the gasoline level, insures that the dash pot is cleared of air and is full of gasoline to avoid the compressibility of air interfering with the operation of the dash pot. A 25 valve 31 at the lower end of the piston 29 closes on upward movement of the piston and opens upon downward movement thereof which permits a free downward movement of the piston.

It is realized that the tension of the spring 23 30 will be increased to some extent as it is compressed and the arc of travel of the arm 20 of the bell crank is arranged to increase its power in its action against the piston 29 as the spring 23 is compressed thus maintaining a substantially constant effort against opening of the suction valve 5 throughout its range of travel.

The fulcrum 26, which supports the rocking lever 25, is mounted for adjustment longitudinally of the lever 25, being formed on a slide 32 which is seated on a saddle 33. The slide 32 has slots 40 34 through which the valve 15 and a pin 35 extend to guide the slide in its longitudinal movement. An adjusting screw 36 projects through the wall of the float chamber, has its inner end 45 connected to the slide 32, and serves as a means for moving the slide longitudinally on the saddle 33 and retaining it in its adjusted position. The connection between the screw 36 and the slide 32 permits relative vertical movement.

50 The saddle 33 is attached to the upper end of a rod 37 which extends downwardly through the body of the structure and has its lower end exposed outside of the carburetor. An adjusting lever 38 is pivoted at one end in a short bracket 55 39 and has its opposite end supported by an adjusting screw 40, the rod 37 engaging the lever 38 between its ends and being adjustably supported thereby. Movement of the adjusting screw 40 raises or lowers the saddle 33 with the parts supported thereon and the lever 38 may be ab- 60 normally raised by suitable connections (not shown) to serve as a primer, which raising movement lifts the valve 15 from its seat to permit an abnormal passage of gasoline for the purpose 65 of starting the engine.

Gasoline is admitted to the float chamber 6 through a float valve 41 of suitable conventional form, the valve being in communication with the source of gasoline supply by the pipe 42. A float 70 43 is located within the float chamber and is provided with a lever 44 which is pivoted at 45 and has its moving end connected with the float valve 41. This valve and its controlling float operate in the usual manner to close the valve 75 when the liquid in the float chamber has raised

to a predetermined level and to open the valve when the liquid falls below that level.

Air is admitted to the float chamber above the liquid level through a port 46 extending through the wall of the float chamber and communicating with a weighted air valve 47. The air valve 47 is normally held against its seat to close the air intake passage by a weight 48 but will raise to open the air passage upon attainment of a sufficient degree of vacuum within the 10 float chamber to lift the weight, such vacuum being attained by suction from the engine transferred through the passages 12, the chamber 13, the U-shaped passage 14 and the gasoline valve 15 which communicate with the float chamber 6. 15

The capacity of the valve 47 is as great or greater than the combined capacity of the passage 14 and valve 15 whereby a greater degree of vacuum will be maintained in the mixing chamber 3 than in the float chamber 6. 20

Operation

Assuming that the carburetor is properly attached to the manifold of an internal combustion engine and that the supply pipe 42 is in communication with a gasoline tank which, for example, is below the level of the carburetor, and that the throttle 2 is properly connected to be manually operated, the engine is started and the suction therefrom acts upon the suction valve 30 5 to open it to permit air to pass through the air passage 4. The vacuum valve 5 opens more or less depending upon the opening of the throttle valve 2 but at all times it sufficiently closes the passage 4 to restrict the passage and set up a 35 vacuous condition in the chamber 3.

The vacuum in the chamber 3 is transferred through the passages 12, the chamber 13 and the U-shaped passage 14 and draws gas from the float chamber above the gasoline level and also gasoline 40 through the control valve 15, the gas and gasoline mixing together in the chamber 13 and the passages and is emitted from the passages 12 into the chamber 3 where it mixes with the incoming air and enters the engine as a combustible gas. 45

The amount of gasoline entering the engine is governed by the control valve 15 and is in substantially direct ratio to the amount of air drawn in through the passage 4. The suction valve 5 50 opens to a greater or less degree depending upon the volume of air passing through the passage 4 and this movement of the suction valve 5 is transmitted to the gasoline control valve 15 in substantially uniform ratio. When the suction valve 5 is closed, as when the engine is not operating, the control valve 15 is in its nearest closed position. This position may be entirely closed or partially open according to the conditions for which the carburetor is adjusted. Opening movement of the suction valve 5 correspondingly opens the gasoline control valve 15 and when the throttle valve 2 is opened to admit a greater amount of gas the suction valve 5 likewise opens to permit the inlet of a greater amount of air and the gasoline control valve 15 opens in a like degree 60 to admit the passage of a greater amount of gasoline. 65

The device may be adjusted as to the amount of opening of the valve 15 and also as to the rate 70 of opening relative to movement of the suction valve 5. The amount of opening of the valve 15 is regulated by the adjusting screw 40 which, through the supporting lever 38, moves the rod 37 and the saddle 33 at its upper end upon which 75

the slide 32, having the fulcrum 26, is supported. This adjustment of the screw 40, therefore, moves the valve 15 upward or downward and may be termed the "idling" adjustment. The rate of opening of the valve 15 is adjusted by means of the screw 36 which moves the slide 32 carrying the fulcrum 26 lengthwise upon the saddle 33. Movement of this slide changes the location of the fulcrum 26 relative to the lever 25 which 5 results in a greater or less movement of the valve 15 relative to movement of the suction valve 5. While the engine is in operation there is always a vacuous condition existing in the float chamber 6 because the vacuum valve 5 actuates to resist 10 entrance of air into the chamber 3 and causing a vacuous condition in this chamber which is transferred through the passages 12, the chamber 13 and the U-shaped passage 14 to the float chamber. The weighted air valve 47 resists entrance 15 of air from the exterior of the carburetor into the float chamber sufficiently to cause vacuum to exist in the float chamber and this valve is sufficiently weighted so that the degree of vacuum attained in the float chamber is sufficient to cause 20 gasoline to flow through the float valve 41 and the supply pipe 42 to the desired height.

In other words, the air valve 47 and its weight will prevent entrance of air to the float chamber through the passage 46 until sufficient vacuum 25 is attained within the float chamber to raise gasoline from the lowest level desired under operating conditions. Upon attaining the predetermined degree of vacuum in the float chamber the air valve 47 will open to permit air to enter the 30 float chamber and this passage of air into and through the float chamber and out through the U-shaped passage 14 has the result of removing gas accumulated in the float chamber by evaporation to be mixed with the gasoline for combustion and also prevents air locks occurring in 35 any part of the system.

The level of the gasoline in the float chamber is controlled by the float 43 and float valve 41 in the usual way. The float will cause the float 40 valve to close when the predetermined level of fluid has been attained and this action will occur whether the level of the fluid supply is above or below the level of fluid in the float chamber so that a constant level of gasoline is maintained 45 in the float chamber under all operating conditions where the fuel supply level may change such as when the level of the vehicle is changed in going up and down hill, etc. A quick opening action or fluttering of the suction valve 5 and its 50 connected parts is prevented by the piston 29 operating in the dash pot 24. This piston can have only a relatively slow upward movement because of the restricted passage of liquid out of the dash pot. Return or closing movement of 55 the suction valve 5 and also the gasoline control valve 15 is unimpeded by action of the dash pot because the valve 31 will open upon downward movement of the piston 29 permitting free ingress of gasoline into the dash pot.

60 Although this specification sets forth the structure as creating and maintaining a constant vacuum in the mixing chamber and the float chamber it is realized that the degree of vacuum probably varies. The structure acts in a manner 65 which tends to create and maintain a constant vacuum and if the degree of vacuum fluctuates the device acts rapidly to return it to balance or predetermined degree. Therefore the definition of the term constant vacuum is to be interpreted 70 as meaning a practical or substantially constant

vacuum which for all purposes in operation answers the purpose of an actual constant vacuum.

The invention is defined in the appended claims and is to be considered comprehensive of all forms of structure coming within their scope. 5

I claim:

1. In a carburetor, the combination of a fuel reservoir, a connection leading from said reservoir to a source of liquid fuel supply, means for maintaining a constant liquid fuel level, less than full, in said reservoir; a main air passage leading to the intake of an internal combustion engine, spring valve means, leading from atmospheric pressure to the main air passage, said main air passage having a cross sectional area capable of delivering the maximum requirements of the engine; a fuel conduit to the main air passage communicating with the fuel reservoir below the liquid level therein through a port, said port supplying the major portion of the fuel, a branch passage of restricted cross sectional area leading from said fuel conduit to the fuel reservoir above the liquid level therein, said fuel conduit and branch passage being so dimensioned and positioned relative to each other and to the main air passage as to cause the pressure reduction within the main air passage to be directed more to said port than to the space above the liquid level for the purpose described. 10

2. A carburetor as set forth in claim 1 but also having means actuated by the inward movement of said spring, valve means for increasing the effective area of said port in a predetermined varying ratio. 30

3. A carburetor as set forth in claim 1 but also having means for diminishing the normal increased pressure exerted by compression of the spring on the opening movement of the spring valve means including a lever arm cooperatively associated with the spring of the spring valve means to vary the leverage therebetween. 35

4. A carburetor as set forth in claim 1 and also having means, actuated by the inward movement of said spring valve means for increasing the effective area of said port in a predetermined varying ratio and means for diminishing the normal increased pressure exerted by compression of the spring on the opening movement of the spring valve means including a lever arm cooperatively associated with the spring of the spring valve means to vary the leverage therebetween. 45

5. In a carburetor, the combination of a fuel reservoir, a connection leading from said reservoir to a source of liquid fuel supply, means for maintaining a constant liquid fuel level, less than full, in said reservoir; a main air passage leading to the intake of an internal combustion engine, spring valve means, leading from atmospheric pressure to the main air passage, said main air passage having a cross sectional area capable of delivering the maximum requirements of the engine; a continuous passage of restricted cross sectional area from the upper part of the fuel reservoir above the liquid level therein, to said main air passage and branching downwards below the liquid level to admit the major portion of the liquid fuel intermediate of said restricted passage. 55

6. In a carburetor, the combination of, an air valve, a spring tending to close said air valve, a fuel valve, a hinged lever with three arms, coacting respectively with said air valve, said spring and said fuel valve, the ratio of movement of one 60

70

75

to the others being predetermined by the location of the arcs of travel for the purpose described.

7. A carburetor comprising, a closed liquid chamber having two compartments therein, one compartment having a valved fuel inlet communicating with a liquid fuel supply, means actuated by the level of liquid in the compartment to actuate said valve to maintain a level of liquid in the chamber less than full, the other compartment having a dashpot mechanism located therein, a yieldingly closed air inlet leading into the first mentioned compartment above the uppermost plane to which the liquid therein rises, a valved outlet leading from the said liquid compartment below the liquid level, said valved outlet communicating with the intake passage of an internal combustion engine, a second outlet leading from the said liquid compartment above the liquid level likewise communicating with said intake passage of the internal combustion engine, means for increasing the size of the valved outlet from the said liquid compartment in proportion to the vacuum induced within the intake passage of said internal combustion engine and means cooperatively associated with the said valved outlet and the dashpot to dampen its movement.

8. A carburetor comprising, a mixing chamber adapted to be connected with the intake passage of an internal combustion engine and having an air inlet, yieldable means opened by suction from the engine and closing said air inlet, a closed liquid chamber having a valved inlet communicating with a source of liquid fuel supply, means actuated by the level of the liquid in the chamber to actuate said valve to maintain a level of liquid in the chamber less than full, a passage communicating directly between the liquid chamber above the liquid level and the mixing chamber, an air valve to the liquid chamber above the liquid level, a valved outlet from said liquid chamber having at least a portion thereof below the liquid level, means actuated by movement of said yieldable means leading to the mixing chamber to govern the opening of said valved outlet whereby liquid fuel is permitted to pass through said valved outlet, said inlet air valve providing for a predetermined amount of vacuum above the level of the liquid fuel at all times, said outlet passageway leading from above the liquid, being unrestricted by any valve whereby some vacuum, under operating conditions, is produced whereby the lighter ends of the liquid fuel will be drawn through this passageway and vapor lock prevented.

9. A carburetor as set forth in claim 8 in which the passage between the liquid chamber above

the liquid level and the mixing chamber includes a portion of a U-shape, and in which the valved outlet from the liquid leads into the medial part of said U-shape for the purpose described.

10. In a carburetor, the combination of an air admission valve arranged to actuate a fuel admission valve, a spring for normally holding said air valve to its seat and against which said air valve acts throughout its travel, means constituting a leverage between said air valve and spring through which the action of the latter is transmitted to said air valve, said means being so shaped and located with said air valve closed that the effective leverage between the valve and spring is increased as the valve opens to compensate for the increase in the resistance in said spring.

11. In a carburetor, the combination of an air admission valve arranged to actuate a fuel admission valve, a spring for normally holding said valve to its seat and against which said valve acts throughout its travel, means constituting a leverage between said valve and spring through which the action of the latter is transmitted to said valve, said means including two lever arms associated with said spring and valve and pivoted about a common axis as a unit, said levers being so disposed with reference to the direction of operation of said valve and spring that the effective leverage between the lever associated with said valve increases upon opening movement of said valve and the effective leverage between the lever associated with said spring decreases whereby the increasing resistance of the spring upon opening of the valve is compensated.

12. A carburetor, comprising an air admission valve arranged to actuate a fuel admission valve, a spring continuously urging said air valve toward a closed position and giving increasing resistance upon opening movement of said valve, a lever structure for actuating said fuel valve and for directing the stress of said spring against said air valve, the portion of said lever structure actuating said fuel valve being so shaped and located with said fuel valve in a closed position as to impart a greater degree of travel of said fuel valve during the early range of movement of said air valve than during the latter range of movement of said air valve, the portion of the lever structure operatively connecting said spring and air valve being so shaped and located as to have an increasing effective leverage favoring said air valve to compensate for the build-up of said spring during the travel of said air valve from closed to open positions.

EDWARD G. ATKINS.
